ATTORNEY

INVENTOR

UNITED STATES PATENT OFFICE.

CHARLES J. PILLING, OF PHILADELPHIA, PENNSYLVANIA.

STETHOSCOPE.

No. 816,854.

Specification of Letters Patent.

Patented Jan. 26, 1909.

Application filed October 18, 1908. Serial No. 388,887.

To all whom it may concern:

Be it known that I, CHARLES J. PILLING, a citizen of the United States, residing in the city of Philadelphia, State of Pennsylvania, have invented certain new and useful Improvements in Stethoscopes, of which the following is a full, clear, and exact description, reference being had to the accompanying drawings, forming a part of this specification.

My invention relates to stethoscopes and has for its object the better and more complete reception and transmission of sound-waves created by its diaphragm when set in vibration.

To this end my improved instrument comprises a suitable supporting means for a vibratable diaphragm, and forming part of a casing of a character to supply a shallow sound chamber, of a back or base plate the inner face of which has a central circular concavity with a spiral concavity surrounding and communicating with the same, an aperture in said central concavity, extending through the base plate, and a sound-conveying tube mounted in said aperture. In its best form I prefer to make such sound-conveying tube as a forked tube, of metal and hence rigid, with its inlet end curved so as to cause it to lie in a plane substantially parallel with the back of the base-plate and with its end screw-threaded to fit a screw-thread on the aperture of the base plate; but these special features are not claimed herein.

In the drawings illustrating my improved device Figure 1 is a plan view of the device, with the rubber ends, detached, of the usual binaural flexible tubes connected thereon. Fig. 2 is a side elevation thereof. Fig. 3 is a plan view of the underface of the base plate of the instrument; Fig. 4 is a vertical sectional view of the instrument, showing also in elevation one form of and method of connecting the rigid sound-conveying tube. Fig. 5 is a plan view and Fig. 6 a sectional view, partly in elevation, of another form of the base-plate and of the mounting thereon of the rigid sound-conveying tube.

Referring now to said drawings, 2 indicates the back or exterior of the base plate, and mounted thereon through an aperture 7 in the region of a central concavity 8 therein is the inlet end 3 of a rigid metallic sound-conveying tube 4 having integral forked branches 4, 4, to the ends of which may be removably attached the flexible tubes 5, 5, of a

known form of binaural device 6. The inlet end of the tube 4 is preferably curved downwardly, as shown in Figs. 2, and 6, in order to bring the tube into substantial parallelism with the back of the base-plate, the forked discharge ends extending beyond the annular rim thereof; though, as shown in Figs. 2 and 4, the single tube 4 may be substituted, mounted in an inclined position relatively to the base-plate, entering an aperture 7 on and towards the side of the central concavity 8 thereof; but the forked form of rigid sound-conveying tube before described, is preferable, and in such case its inlet end 3 is screw-threaded at 7^a (Fig. 6), the aperture 7 in the base-plate is threaded to correspond, and a flange plate 6 mounted on the end 3 beyond the screw threads in order to seat on the base-plate, as shown in Figs. 5 and 6, and in that case the aperture 7 is central in the concavity 8 as shown in Figs. 1, 2, 6 and 7.

The stethoscope body consists of a back or base plate 2 constructed as illustrated in the several figures in which the inner face thereof is provided with means to accumulate and deflect the sound waves produced in the sound chamber of the instrument by the vibration of its diaphragm; these means consisting of a spiral groove on said inner face of the base plate, forming ribs 9^a and consequently a series of shallow chambers 9, between them, resulting from the spiral groove in the face of the plate; the spiral groove proceeding from the outer circular edge of the plate towards the center and terminating in a central circular concavity 8, forming a secondary sound chamber, from which the sound waves are discharged through an aperture 7 therein, and which may be central thereof, as in Figs. 1 and 2, or at the side thereof as in Fig. 4, depending on which of the two described forms of rigid sound conveying tube is employed. Peripherally mounted on this base-plate 2, such as by co-acting screw threads, is a ring 10 having an inwardly projecting flange 11 adapted to support the usual vibratable diaphragm 12 by compressing its extreme annular edge or rim between such flange and the annular edge or rim of the base plate 2, the ring 10 being of such width that when the parts are assembled there will be a shallow space, forming the usual sound chamber space between the diaphragm and the inner face of the base plate in addition to the spiral concavity and central concavity, in the latter.

Having thus described my invention, I claim as new and desire to secure by Letters Patent:—

A stethoscope provided with a diaphragm, 5 an annular ring supporting the same, and a base plate the inner face of which is provided with a central circular concavity with a spiral concavity surrounding and communicating with the same, said elements forming in combination a sound-chamber, with a sound-cor-

veying tube mounted in an aperture in said base plate and communicating with the central concavity therein.

In testimony whereof, I have hereunto affixed my signature this 29th day of Sep- 15 tember A. D. 1906.

CHARLES J. PILLING.
